L. A. M. PHELAN ET AL.

ELECTRICAL SWITCH

Filed Dec. 8, 1922

UNITED STATES PATENT OFFICE.

LOUIS A. M. PHELAN AND CLIFFORD HOTCHKISS, OF BELOIT, WISCONSIN; SAID HOTCHKISS ASSIGNOR TO SAID PHELAN.

ELECTRICAL SWITCH.

Application filed December 8, 1922. Serial No. 605,635.

To all whom it may concern:

Be it known that we, LOUIS A. M. PHELAN and CLIFFORD HOTCHKISS, residents of Beloit, in the county of Rock and State of Wisconsin, respectively, have invented new and useful Improvements in Electrical Switches, of which the following is a full, clear, concise, and exact description, reference being had to the accompanying drawings, forming a part of this specification.

Our invention relates to electrical switches of the type having electrodes or contacting elements which are enclosed in a sealed container and which are moved into and out of contact making position by a force external to this container.

More particularly our invention refers to a device of the above character wherein movable electrodes are disposed within an hermetically sealed glass container located in close proximity to a movable magnetized armature, the magnetic lines of force from which serve to operate the movable electrodes within the glass container.

An object of our invention is to produce a contact device of the above character in which no appreciable deterioration of the contact parts will occur, and at the same time to provide a device which can be readily operated by the expenditure of a very small quantity of energy.

Another object of our invention is to produce a device of the above character in which a liquid electrode such as mercury is used for one of the contact parts, and to provide an operating mechanism for such a device which does not necessitate tilting of the container, and which is not easily actuated accidentally.

Another object of our invention is to provide a thermostatic temperature regulating device making use of the above type of electrical contactor.

A further object of our invention is to provide a device of the above character which is simple to construct and which will satisfactorily operate for long periods of time, even when subjected to serious mechanical abuse and when used to interrupt a very large quantity of current at a substantial voltage.

Further objects and advantages will appear upon reference to the following speci-

fication and the accompanying drawing, in which:

Figure 1 is a front view of a form of our device with the cover removed;

Fig. 2 is a sectional view taken on line 2-2 of Fig. 1, the cover also being shown in section;

Fig. 3 is a sectional view taken substantially on the line 3-3 of Fig. 2, showing in detail the contactor tube and the actuating armature when the device is in open circuit position;

Fig. 4 is a view similar to that of Fig. 3, but showing the device in closed circuit position;

Fig. 5 is a sectional view taken substantially on line 5-5 of Fig. 4;

Fig. 6 is a sectional view taken on line 6-6 of Fig. 4; and

Fig. 7 is a sectional view taken at line 7-7 of Fig. 1.

The device that comprises our invention consists in a general way of a contactor tube or container 1 mounted adjacent a permanent magnet 2 of horseshoe form, and a rocking armature member 3 for operating the contactor elements in the tube 1. The armature 3 is operatively connected to a spiral bi-metallic thermostatic element 4 which serves to actuate the device upon a sufficient change in temperature of the surrounding medium. The parts are mounted upon an insulated base 5 provided with a cover 6.

The contactor tube 1 is preferably evacuated and filled with a gas such as hydrogen which is inactive toward the parts contained within the tube even in the presence of heat.

The tube 1 is provided at one end of its underside with an extension chamber 6 filled with a body of conducting fluid such as mercury 7. The mercury 7 is adapted to bridge a pair of electrodes comprising a fixed electrode 8 and a movable electrode 9. The electrode 9 is mounted upon a hinged armature member 10 which is hinged to a leading-in wire or support 11. The hinged member 10 is provided with two knuckles 12 and 13 which embrace the support 11 near its end; the hinged member is retained in position on the support 11 by a collar 14 placed between the knuckles 12 and 13 and tightly embracing the support 11, as shown.

The two separate knuckles 12 and 13 provide considerable less bearing surface upon the support 11 than would the member 10 if made continuous with but one knuckle at this point and thus unnecessary frictional losses are avoided. The leading-in wire or support 11, together with the fixed electrode 8 are mounted by being sealed in a glass shank 15 at the end of an inwardly directed extension 16 in the tube 1.

The electrode 8 and the support 11 are connected to the flexible lead wires 17 which serve to connect the device in an external circuit. The hinged member 10 is provided with a back stop 18 which is constructed to rest upon the tubular extension 17 when the device is in open circuit position as in Fig. 3 and to contact with the wall of tube 1 when the device is in closed circuit position—as shown in Fig. 4.

The armature 3 is pivoted above the tube 1 at a point opposite the hinged armature member 10 upon a shaft 19 mounted on the base 5. A pin 20 at the end of shaft 19 serves to retain the armature 3 upon the shaft. An end 21 of the armature 3 is made with a reduced cross-section in order to concentrate the magnetic lines of force emanating therefrom. Stops 22 and 23 are mounted upon base 5, in the position shown, to properly limit the rocking movement of the armature 3. The armature 3 is further provided with an operating lever 24 which is engaged by an eyelet 25 formed at the end 35 of a rod 26 which in turn is mounted upon and operated by the thermostatic element 4. The rod 26 is fixed to the thermostatic element 4 by inserting a bent portion of its end in an opening at 27 in the element 4 and by means of a threaded rod and nut at 28.

The magnetic circuit of the device is through the upper arm of permanent magnet 2, through the air-gap from magnet 2 to armature 3, through another air-gap to the hinged armature 10 within tube 1 and through a third air-gap to the lower arm of magnet 2. The flux of this circuit is sufficient to cause the hinged armature 10 within the tube 1, to closely follow any movements of the armature 3 at the exterior of tube 1.

The thermostatic element 4 is mounted at its inner end to a post 29 which in turn is 55 rotatably mounted on the base member 5. The shape of the spiral thermostatic element 4 may be adjusted by a screw 30 which extends through the inner coil 4a of the spiral element and into the post 29. By turning 60 the screw 30 inwardly, the spiral thermostatic element may be compressed and by turning the screw 30 outwardly, the spiral element will be permitted to expand slightly. An opening 31 is provided in the outer 65 turn of the spiral element in order to per-

mit access by means of a screw-driver to the screw 30.

The angular position of post 29 may be adjusted by means of a link 32 fixed thereto and by an attached mechanism about to be 70 described. A pin 33 is fixed in the end of the link 32 and is retained between clamping members 34 and 35, which are held in clamping relation with the pin 33 by means of a screw 36. A pin 37 mounted in a fixed post 75 38 is also retained between the clamping members 34 and 35. The clamping member 35 may be extended to form an operating lever 39, which terminates in a handle 40 extending to the exterior of the casing 6. In order to adjust the thermostatic element 4 to operate the contactor when a desired temperature occurs, the spiral element is first roughly adjusted by means of the screw 30 so that the armature 3 will freely rest at 80 some point between the pegs 22 and 23. The device can then be very accurately regulated by movement of the handle 40, which will result in a slight turning of the post 29 and the spiral thermostatic element 4 about their common axis.

The magnet 2 may be retained on the base 5 by clamping members 41, 42 and 43, which are retained in position by screws 44. The clamping member 41 may be extended also to serve to clamp the tube 1 in position. A clamp 45 also serves to further retain the tube 1. A strip of felt 46 may be used to cushion the tube 1 from the magnet 2.

The leading-in wires 17 to the tube 1 may be extended to suitable binding posts such as 47, located upon the base 5. The base 5 may be formed with suitable openings 48 and 49 providing for attaching screws enabling the device to be mounted upon a wall.

The cover 6 may be attached to base 5 as by screws 50. The cover 6 is preferably provided with openings 51, which permit free circulation of the air around the thermostatic element 4. A thermometer 52 may be mounted upon the device to serve as a guide in adjusting the lever 40.

The device when used may be mounted upon a vertical wall of the room or compartment, the temperature of which is to be regulated. The binding posts 47 may be connected in series with any suitable and usual type of electrical circuit used for the control of heating apparatus. It may be assumed that when the circuit through the tube 1 is open that the heating equipment will not be in operation but that upon closing the circuit through tube 1 the heating equipment will begin to operate. Therefore at a time when the room temperature is at a satisfactory point, the lever 40 should be adjusted so that the contacts in the tube 1 will just be in open circuit position. Then when a sufficient drop in temperature occurs the thermostatic element 4 will turn the

armature 3 which will be followed in its movements by the armature 10 within the tube and consequently the electrode 9 will be thrust into the mercury 7 and the circuit 5 will become closed. The heating equipment will then operate to again restore the proper room temperature. When the normal temperature is reached the parts will go through reverse movements to again open the circuit 10 through the tube 1 and thus stop the operation of the heating equipment.

We desire that our invention be broadly interpreted and limited only by the prior art and by the scope of the appended claims.

Having thus described our invention, what we claim as new and desire to secure by Letters Patent in the United States, is:

1. An electrical contactor comprising a hermetically sealed container, an integral inwardly directed extension to said container, a magnetic armature pivotally mounted on said extension, and a contact mounted on said armature.
2. An electrical contactor comprising a hermetically sealed container, an integral inwardly directed extension to said container, a stationary electrode and a magnetically operated movable electrode supported by said extension.
3. An electrical contactor comprising a hermetically sealed container, an integral inwardly directed extension to said container,

a stationary electrode and a magnetically operated movable electrode supported by said extension, and leading-in wires to said electrodes introduced into said container through said extension.

4. An electrical switch comprising a permanently magnetized member, a contactor tube having at least one of its electrodes interposed between the poles of said magnetized member, said contactor having a movable electrode and a magnetizable member contained therein, a rocking armature located in proximity to said magnetized member and said movable electrode, and a thermostatic element to actuate said rocking armature whereby said movable electrode opens and closes the electrical circuit through said contactor tube.

5. An electrical switch comprising a magnetizable member, a contactor tube interposed intermediate the poles thereof, said contactor tube comprising a movable electrode, a rocking magnetizable element interposed intermediate the poles and said magnetizable member, and means for actuating said rocking magnetizable element in order to influence the movable electrode of said contactor.

In witness whereof, we have hereunto subscribed our names.

LOUIS A. M. PHELAN.
CLIFFORD HOTCHKISS.
